INSOLE AND METHOD OF MAKING
INSOLES

Everett E. Murphy, Newburyport, Mass., assignor
to United Shoe Machinery Corporation, Paterson, N. J., a corporation of New Jersey

Application May 19, 1933, Serial No. 671,883

24 Claims. (Cl. 12—146)

This invention relates to insoles and to methods of making insoles and is herein illustrated with reference to the manufacture of shoes having uppers secured in lasted position by cement.

5 In the manufacture of shoes in which uppers are secured in lasted relation to insoles by cement it is desirable that the insole be provided with a strong and substantially rigid rib or lip to which the upper may be temporarily secured to hold the upper in lasted position during the setting of the cement by which the upper is permanently attached to the insole. The lip should be strong enough to withstand the outward tensions of the upper after it has been secured to the lip 10 by metal fastenings or otherwise, thereby insuring that the lip will not tear or pull away from the outer face of the insole before the upper attaching cement has set. Moreover, it is of great advantage in this type of work to have the rib or lip so disposed relatively to the outer face of the insole that it will have a tendency to turn inwardly away from the feather portion of the insole and thus assist in holding the upper tightly in lasted position while the cement is setting.

15 Objects of the present invention are to provide an improved insole which will be especially adapted for use in the manufacture of a shoe having its upper lasted by cement and to provide an improved method by which such insole may be produced.

20 One aspect of the invention comprises an improved insole, preferably of leather, which, as illustrated herein, is provided with a rib or lip formed from material integral with the insole and folded over upon itself to produce a double or two-ply lip. As illustrated, the lip is located at the inner edge of the feather portion and extends substantially from the toe to the heel breast line, the continuity of the lip being broken at the toe end of the insole. Preferably, and as illustrated, the lip is inclined inwardly toward the outer face of the insole so that it will resist being brought into an upright position, thus causing the lip to assist in holding a shoe upper tightly in lasted position. The outer face of the two-ply lip may, if desired, have stiffening material such as shellac thereon to render the lip more resistant to outward bending in response to the tension 25 of the upper after the latter has been secured to the lip.

25 In another aspect the invention comprises an improved method of making insoles which, as illustrated herein, consists in providing an insole with a double or two-ply lip by channeling in

from the edge face of the insole a distance approximately equal to the feather portion thereof, thereby reducing the feather portion and forming a single continuous outer layer or channel flap. An adhesive may, if desired, be applied to the upper surface of the flap and the flap is then turned back upon itself to form a double layer of material which is about half as wide as the feather portion of the insole. The double layer of the flap is then turned upwardly and inwardly 10 against the outer face of the insole and set in such position, thereby producing an inwardly inclined lip of double thickness. Preferably, the feather portion of the insole is reduced an amount somewhat less than the thickness of the upper 15 materials to be used so that a relatively thin channel flap will be formed which, when folded over upon itself, will produce a strong double lip that is about half as wide as the feather portion and at least as thick as the upper materials which 20 are to be secured thereto. As stated, the outer face of the double lip may, if desired, be treated with a stiffening solution which will penetrate into the two layers of material and thus stiffen the lip and render it more resistant to outward 25 bending.

25 The above and other aspects of the invention will appear more fully from the following detailed description when read in connection with the accompanying drawing and will be thereafter 30 pointed out in the claims.

In the drawing,

Fig. 1 is a side elevation of a portion of a lip-turning machine arranged to carry out the present invention;

Fig. 2 is a plan view of the mechanism shown in Fig. 1 with the lower portions of the machine omitted;

Fig. 3 is a side elevation partly in section of the upper portion of the lip-turning machine 40 shown in Fig. 1 with the parts in a different position;

Fig. 4 is a fragmentary view of the outside channel forming instrumentalities of a channeling machine operating upon an insole, the insole 45 being shown broken off and in section;

Fig. 5 is a fragmentary view showing only the work-engaging ends of the lip forming instrumentalities of the lip-turning machine, the parts being shown operating upon the outer portion 50 of the channel flap;

Figs. 6, 7, and 8 are views similar to Fig. 5 illustrating further steps in the lip forming operation; and

Fig. 9 is a transverse sectional view of a por- 55

tion of the insole showing the lip after the lip-forming operations have been completed.

In practicing the method illustrated herein a channel is first formed around the periphery of a relatively thin insole 10, (Fig. 4) preferably a leather insole, to form an outer layer or flap 12 which terminates at about the heel breast line. The channel cut extends inwardly from the edge face of the insole in a plane substantially parallel to its lower face, thereby separating the outer layer or flap 12 from the body portion or inner layer of the insole and leaving a reduced feather portion 14 the upper surface of which is parallel to the inner face of the insole. The channel 15 extends inwardly from the edge face of the insole a distance equal to the amount it is desired to have the shoe upper overlap the margin of the insole, this distance usually being from three-eighths to a half inch at the forepart of the insole and becoming somewhat greater at 20 the portion of the shank adjacent to the heel breast line in order to allow for the width of the wings of a counter. The channel cut is preferably spaced from the outer face of the insole a distance somewhat less than the thickness of the upper materials to be used in the shoe in order to provide a relatively thin channel flap. This distance may, however, be greater in cases where 25 no filler is to be applied to the shoe bottom prior to the attachment of an outsole.

The channeling operation may be performed, for example, with the aid of a sole-channeling machine of the type disclosed in United States Letters Patent No. 1,023,801, granted April 23, 35 1912, upon an application filed in the name of Frederic E. Bertrand. As fully shown and described in the patent mentioned, the sole-channeling machine is provided with a work support or table and has inside and outside channel forming instrumentalities cooperating therewith which 40 are adapted to operate on the feather or marginal portion of an insole. Fig. 4 illustrates the work engaging portions of the outside channel forming instrumentalities of the machine operating on the insole 10 and will give a good idea 45 of how the outside channel is made. As shown, the insole is supported on a work-supporting table 16 with one edge against an edge gage 17. The insole is fed along the table by a presser foot 18 which is mounted in an oscillatory carrier (not shown) and which, during the feeding movement, presses yieldingly against the insole to grip the portion which has just been cut between the presser foot 18 and an edge knife 20 which is also mounted on the carrier directly below the presser foot. On the forward stroke of the oscillatory carrier the insole is fed along the table 16 and, on the backward stroke, a work retainer or bearing foot 22 moves downwardly against the insole to hold the latter stationary 50 while the presser foot 18 and the edge knife 20 move backwardly to their original positions, the presser foot at this time being raised from engagement with the insole. It is during this rearward movement of the carrier that the edge knife 20 performs its function of cutting a slit 55 in the feather portion of the insole to form the outside channel.

After the insole 10 has been provided with an outside channel which extends around the periphery of the insole substantially from breast line to breast line, to form the channel flap 12, the next step in the method consists in utilizing the single channel flap to produce a lip or rib 70 on the outer face of the insole which will be

strong enough to serve as a means for holding a shoe upper temporarily in lasted relation to the insole while the cement is setting which is to secure the upper permanently to the insole. Preferably, the upper surface of the channel flap 12 is coated with cement or other suitable adhesive before the lip forming operations are performed, although the adhesive may, if desired, be omitted since it is not absolutely essential for the formation of the lip. In order to 10 facilitate operating upon the single channel flap 12 to form the lip or rib, that portion of the flap which is located at the toe end of the insole is snipped off by a reciprocating cutter extending across the toe portion of the insole at a distance 15 from its end equal to the width of the reduced feather portion 14, the downward movement of the cutter being limited so that it will not cut into the body of the insole. In this way a space is provided which separates the channel 20 flap at the toe end of the insole.

The insole 10 is now ready for the formation of a rib or lip along each margin of its outer face, these lips to be of double thickness and to extend from the toe end of the insole substantially 25 to the heel breast line. The manner in which the insole lips are formed is illustrated in Figs. 5 to 9, inclusive, and the mechanism with the aid of which the steps of the method are accomplished is illustrated in Figs. 1 to 3. This mechanism is 30 illustrated herein as embodied in a lip-turning machine of the type disclosed in United States Letters Patent No. 638,010, granted November 28, 1899, upon an application filed in the name of John B. Hadaway. The construction and operation of this machine are well known to those skilled in the art and, since reference may be had to the patent mentioned for a full disclosure thereof, only those parts of the machine which have a direct connection with the present invention 35 have been illustrated in the drawing.

As shown and described in the patent mentioned above, the lip-turning machine is provided with a horizontal drive shaft 24 (Fig. 1) having mounted thereon a worm 26 which, through gearing 28 and 30, drives a vertical shaft 32 and an inclined shaft 34 which carry respectively at their upper ends a rotatable work support 36 and a feed wheel 38. The feed wheel 38 is located at an angle above the work support 36 and the latter is spring-pressed upwardly against the feed wheel, these members being rotated in opposite directions by the gearing 28, 30 so that the work, for example, an insole, will be gripped between the two members and thus fed along the upper 50 surface of the work support. The lip-turning machine is also provided with a work gage 39 against which the edge face of the insole may be located as it is fed along the work support, thereby maintaining the insole always in proper relation to the 55 lip-turning instrumentalities.

The lip turning instrumentalities comprise, in part, a lip-forming or -setting tool 40 and a slashing knife 42 carried by a holder 43 on the lower end of a slide member 44 (Fig. 1). The 60 slide member is mounted in an inclined guideway 46 formed in a portion of the frame and is reciprocated in the guideway by means of a link 48 which connects the slide member 44 to the upper end of an oscillating lever 50 actuated by an eccentric 65 formed on the drive shaft 24, as fully shown in the Hadaway patent referred to. A plow or lip-turning tool 52, adjustably mounted on the frame of the machine, is adapted to enter the channel in the insole as the latter is fed 70

along the work support and to turn up the channel flap into a position in which it may be acted upon by the reciprocating lip-setting tool 40, the latter delivering to the turned-up portion of the flap a series of sharp quick blows in rapid succession which weaken the fibres of the flap so that it can be bent backwardly and downwardly against the outer face of the insole. As the turned-back portion of the flap passes by the lip-setting tool 40 it comes into engagement with a rubbing tool 54, best shown in Figs. 2 and 3, which engages the flap and further assists in maintaining it in its turned-back position. During the pounding action of the lip-setting tool the slashing tool 42 makes a series of small indentations or cuts along the outer edge of the turned-back portion of the flap which also tends to weaken the fibres and thus to facilitate the lip-turning and -setting operations. As shown in Figs. 1 to 3, inclusive, the lip-turning, setting and slashing tools are adjustable relatively to each other so that they may be made to operate on insoles having different sized channel flaps and feather portions of varying thicknesses.

In order that the lip-turning machine may be utilized for turning back the single channel flap 12 of the insole in such a manner as to form a double or two-ply lip, as hereinafter set forth, the machine has been provided with mechanism which is arranged to permit only a predetermined width of the channel flap to be turned up and backwardly into a substantially flat position, this mechanism being then moved out of operative position so that the insole may be fed through the machine again to turn up the remaining portion of the flap and press it backwardly against the outer face of the insole. The mechanism for accomplishing this comprises a bracket 58 (Fig. 1) mounted above the guideway 46 and forming the upper side of said guideway. The bracket 58 has a vertical wall 60 which extends upwardly from the base of the bracket and at its forward end supports a fixed horizontal stud 62 which is held therein by a set screw 64. The stud 62 forms the pivot for a lever 66 which has adjustably secured to its forward end, by a screw 68 in a slot 69 (Fig. 3), the shank portion 70 of a carrier member 72. The body portion of the carrier member 72 is perpendicular to its shank portion and has formed therein a slot or guideway 73 which extends longitudinally of the body portion of the carrier and in which is yieldingly mounted for sliding movement a slide member 74. Secured to the forward or exposed face of the slide member 74 is a lip-controlling arm 76 which is fastened to the slide member 74 by a screw 78 passing through a slot 80 in the arm 76 so that the latter may be adjusted into different positions longitudinally of the slide member 74. The central portion of the slide member has an elongated opening formed therein in which is mounted a small compression spring 82. The upper end of the spring extends beyond the slide member 74 and engages the under side of a forwardly extending arm of a small angle plate 84 which is fastened to the upper end of the carrier member 72 by a screw 86. It will be seen from the above description that the lip-controlling arm 76 is not only adjustable longitudinally of the lever 66 and lengthwise of the slide member 74, but that it is also free to yield upwardly in the carrier member 72 against the action of the compression spring 82 whenever pressure is exerted against the lower end of the arm. The downward movement of the lip-controlling arm is limited by means of a

screw 88 which extends through a slot in the lower end of the slide 74.

The rearwardly extending arm of the lever 66 has formed on its end a horizontal boss 90 (Fig. 2) provided with an opening 92 in which is slidably mounted a spring-pressed plunger 94 having an enlarged head and shank portion which extends through a smaller portion of the opening 92 and has pinned to its outer end a hand nut 96 by which the plunger can be moved lengthwise of the opening. A compression spring 98 tends normally to force the plunger to the limit of its inward movement, as viewed in Fig. 2, this limit being determined by the inner side of the hand nut 96. The head of the plunger 94 has a small projection or knob 95 formed thereon which is adapted to enter small recesses 100, 102 (Figs. 1 and 3) formed in the rear portion of the vertical wall 60, these recesses being located in predetermined positions heightwise of the wall. When the projection 95 on the plunger is positioned in the upper recess 100 the lip-controlling arm 76 will have been moved downwardly to a position which is just above the work-supporting table 36 as shown in Fig. 1. In this position the controlling arm is adapted to cooperate with the lip-turning and lip-setting tools in forming a double lip on the insole. When the projection 95 is located in the lower recess 102, the lip-supporting arm will be raised away from the work table, as shown in Fig. 3, and will be out of the way of the lip forming instrumentalities.

The lever 66 has a third arm 104 formed thereon which extends downwardly therefrom just below the fulcrum 62. The arm 104 carries a horizontal pin 106 which projects forwardly, as viewed in Fig. 1, into a slot 108 formed in the upper extremity of an upwardly extending arm 110 which is fixedly secured to the end of a horizontal shaft 114 by a clamping screw 112. The shaft 114 extends through a bearing in the central portion of the frame and has the work gage 39 aforementioned secured to its other end by a screw 116 which enters a threaded opening in the end of the shaft. The gage 39 projects forwardly or toward the left, as viewed in Fig. 1, and is curved in such a manner that it will pass the inner edge of the work support 36 in close proximity thereto and thus be in a position to act as a gage for determining the position of the insole on the work support. When the lever 66 is moved from the position shown in Fig. 1 to the position shown in Fig. 3 by means of the spring plunger arrangement 94, the lower arm 104 of the lever 66 will swing forwardly and will cause the upwardly extending arm 110 to rotate the shaft 114 in a counterclockwise direction, thereby swinging the edge gage 39, downwardly away from its operative position adjacent to the inner edge of the work support 36. In this way the lip-controlling arm 76 and the edge gage 39 are simultaneously moved into or out of operative positions merely by changing the position of the lever 66.

In the use of the machine in accordance with the method of making insoles disclosed herein, the insole 10 with the outside channel formed therein is mounted on the work supporting table 36 with the edge which is to be operated upon in contact with the edge gage 39, the lever 66 being positioned as shown in Fig. 1 with the plunger 94 located in the upper recess 100 so that the lip-controlling arm 76 will be close to the table and will thus be in a position to bear yieldingly against the upper surface of the channel flap 12 at a

point approximately midway between the inner and outer edges thereof. The work support 36, which, as stated, is urged upwardly by a compression spring during the lip forming operation, 5 will force the edge of the insole against the feed wheel 38. The machine is tripped and the insole is fed past the lip-turning instrumentalities so that the lip turning tool 52 can enter the channel slit at the heel breast line and cause that 10 portion of the channel flap 12 which is in front of the lip-controlling member 76 to be turned upwardly and backwardly to an angle which is somewhat greater than 90°, or, in other words, so that it will be inclined inwardly of the feather portion 15 of the insole against the forward surface of the lip-controlling arm 76, as shown in Fig. 5. This turned-back portion of the channel flap, which is substantially half of the full width of the flap, is now fed past the plow 52 and lip-controlling member 76 and is engaged by the reciprocating lip-setting tool 40 which delivers thereto a series of sharp quick blows, thereby substantially weakening the fibres along the outer edge of the turned-back portion. The outer half 20 of the channel flap is thereupon bent backwardly and downwardly by the force of the blows until it lies closely against the upper surface of the inner half of the flap, as shown in Fig. 6. The slashing knife 42 also assists in the turning operation by making a series of small indentations or 25 cuts in the flap, thereby weakening the fibres of the leather to such a degree that the outer portion of the flap will have practically no tendency to return to an upright position after the turning operation has been performed.

If cement or other adhesive has been applied to the upper surface of the channel flap it will now be tacky enough to cause the turned-back portion to adhere to the inner portion and the adhesion of these portions is further assisted by the rubbing tool 54 (Figs. 2 and 3) which bears against the double thickness of material as the insole is fed along and presses the two layers forcibly together, thereby insuring that a permanent cement bond will be obtained. If no adhesive is used the outer portion of the flap will be turned back substantially as described but will not, of course, adhere to the inner portion of the flap. The insole 10 is fed through the machine until the outer half of the entire channel flap 12 has been turned back in the manner described, thus forming a double layer of material around the periphery of the insole extending from breast line to breast line. Figs. 5 and 6 of the drawing show 50 this step of the method, the lip-controlling tool 76 and lip-turning tool 52 having been left out of Fig. 6 in order to show more clearly the operation of the lip-setting and lip-slashing tools which are located rearwardly of the lip-turning and lip-controlling tools.

Before the next step of the illustrated method is performed, the pivoted lever 66 is moved from its operative position, as shown in Fig. 1, to its inoperative position, as shown in Fig. 3, thus withdrawing the lip-controlling member 76 and the edge gage 39 from the positions in which they contact with the insole 10. The insole is placed again upon the work supporting table 36 and is held in such a position that, as it is fed along the work support 36, the lip-turning tool 52 will enter the inner portion of the channel and turn up the double thickness of material to the position shown in Fig. 7, thereby forming an upwardly and inwardly extending rib or lip 120. It will be noted in Fig. 7 that the edge gage 39 has been

lowered from its operative position adjacent to the inner edge of the work support 36 so that the insole 10 can now be located with its feather portion extending inwardly of the machine well beyond the inner edge of the work support, thereby permitting the feed wheel 38 to contact with the inner portion of the feather to feed the insole, and also permitting the lip-turning tool 52 to be in a proper position to operate on the double portion of the channel flap. As the turned-back 10 portion of the double lip 120 passes by the lip-setting tool 40, it is subjected to a series of sharp blows which bend the lip backwardly and force it downwardly against the outer face of the insole, as shown in Fig. 8. The slashing tool 42 15 again forms a series of small indentations along the outer edge of the lip which tend to weaken the fibres and thereby to cause the lip to remain permanently in an inwardly inclined position. After the insole has been fed completely through 20 the machine so that the entire lip has been turned back in the manner described, the insole is removed and the lever 66 is again moved into the position shown in Fig. 1, thus locating the mechanism in a proper position for operating on the 25 next insole.

Fig. 9 shows a portion of the insole 10 in section after the lip turning operations have been performed. It will be noted in this figure that the double lip 120 does not lie perfectly flat against 30 the outer face of the insole but is inclined inwardly in such a position that its inner side forms a sharply acute angle with the outer face of the insole. The above-described insole is particularly adapted for use in making a shoe having its 35 upper secured in lasted relation to the insole by cement in accordance with the methods disclosed in Letters Patent of the United States No. 1,932,545, granted October 31, 1933, upon an application filed in the name of George Goddu and 40 in an application Serial No. 576,342, filed Nov. 20, 1931 in his name. In practicing the methods referred to, a shoe upper is secured in lasted position against the inclined lip by metal fastenings, such as staples, while the cement is setting, 45 the stapling anvil passing under the lower side of the lip so that the latter will be raised to an upright or substantially vertical position during the staple inserting operation. After the upper has been stapled to the lip, a trimming operation 50 is performed to remove the upstanding portion of the lip and the marginal portion of the upper which is secured to the lip. The trimming cut may be made above the line of staples, thereby leaving the staples to assist in holding the upper 55 in lasted relation to the insole, or, if desired, the cut may be made below the staples so that they will be removed from the shoe bottom with the trimmed portions of the upper and lip and thus leave a comparatively smooth bottom surface on 60 the shoe suitable for the attachment of an outsole.

Before the insole is utilized in a shoe of the type referred to, the inclined double lip 120 may, if desired, be coated on its outer face with a 65 stiffening solution such, for example, as that described in the Goddu application referred to, this solution being made up chiefly of shellac, alcohol and acetone. The stiffening solution will penetrate into the fibres of the leather and thereby impregnate the double lip in such a manner as to cause the lip to become relatively stiff and rigid when the solution has thoroughly dried.

Having thus described my invention, what I 75

claim as new and desire to secure by Letters Patent of the United States is:

1. An insole having a lip thereon formed from a single layer of material separated from the 5 marginal portion of the insole, from its edge face inwardly and folded over upon itself to produce a lip of double thickness.
2. An insole having an inwardly inclined double lip formed from a single continuous layer of material 10 split inwardly from the edge face of the insole, said lip being integral with the insole.
3. An insole having an integral lip formed from a thin layer of material separated from the 15 marginal portion of the insole from the edge thereof inwardly, said material being folded over upon itself and laid back against the outer face of the insole to produce an inwardly inclined double lip.
4. An insole having a folded-over lip which is 20 composed of a single outer layer of material separated from the feather portion of the insole by a cut passing through the edge face thereof, said lip being set against the outer face of the insole to produce an inwardly inclined double lip.
5. An insole having a reduced feather portion 25 and a two-ply lip formed from a continuous layer of material separated from said feather portion.
6. An insole having a wide feather portion of 30 reduced thickness and an integral lip of double thickness composed of a single layer of material channeled from said feather portion, one thickness only of the double lip being joined to the insole.
7. An insole having a reduced feather portion 35 and an inwardly inclined double lip formed entirely from an outer layer of material of substantially uniform thickness separated from said feather portion.
8. An insole having a reduced feather portion 40 and a folded lip of double thickness approximately equal in width to half the width of said feather portion, said lip being inclined away from said feather portion toward the outer face of the insole.
- 45 9. An insole having a reduced feather portion of predetermined width and an integral lip of less width than the feather portion, said lip being composed of two thicknesses of material one thickness only of which is joined to the insole and being set in an inwardly inclined position to cause it to resist being brought into an upright position.
- 50 10. An insole the feather portion of which is reduced by about one third, said insole having formed at the inner edge of said feather portion an inwardly inclined rib of double thickness 55 which is integral with the insole and is substantially as thick as the reduced feather portion.
- 55 11. An insole having a reduced feather portion of predetermined width and a two-ply lip at the inner edge of the feather which is about half as wide as said feather and is inclined inwardly to form a sharply acute angle with the outer face of the insole, the upper side of said lip being coated with stiffening material.
- 60 12. An insole having an inwardly inclined double lip formed entirely of material separated from the feather portion of the insole, whereby said portion is reduced, said lip being impregnated on its upper side with shellac.
- 65 13. An insole having an integral lip of double thickness extending inwardly from the inner edge of the feather portion thereof, said lip being composed of a single continuous layer of material separated from the margin of the insole in order 70 to reduce said feather portion.
14. An insole having a reduced feather portion of predetermined width and an upper channel flap the outer portion of which is folded over and secured to its inner portion and forms a double lip at the inner edge of said feather portion. 75
15. An insole having a reduced feather portion and an inclined lip at the inner edge of said feather portion, said lip being formed from a layer of material of uniform thickness which is integral with the insole and which is folded over upon itself and permanently secured in such position to produce a lip of double thickness. 10
16. An insole having a reduced feather portion of substantial width and an integral lip formed 15 from a layer of material separated from said feather portion, the outer half of said material being folded over and cemented to the inner half to produce a double lip.
17. An insole having a reduced feather portion 20 of substantial width and an inwardly inclined two-ply lip located at the inner edge of said feather portion, said lip forming a sharply acute angle with the outer face of the insole and being composed of a single continuous layer of material 25 integral with the insole, the outer half of said material being turned back upon the inner half and cemented thereto, thereby forming a two-ply lip one thickness only of which is joined to the insole. 30
18. That improvement in methods of making insoles which consists in channeling in from the edge face of an insole to separate an upper layer from a lower layer, turning the upper layer back upon itself to form a double layer, and turning 35 the double layer back against the outer face of the insole to form an inwardly inclined lip of double thickness.
19. That improvement in methods of making insoles which consists in channeling in from the 40 edge face of an insole in a plane parallel to its inner face, turning the outer flap of the channel back upon itself to form a double layer of material, and turning said double layer back against the outer face of the insole to form an inwardly 45 inclined double lip.
20. That improvement in methods of making insoles which consists in applying adhesive to the marginal portion of the outer face of an insole, cutting a channel inwardly from the edge 50 face of the insole, said channel extending in a plane parallel to the inner face of the insole and separating the margin of the insole into a thin upper layer and a thick lower layer, turning the outer portion of said upper layer back against 55 the inner portion thereof so that the adhesive will cause the two layers to stick together and form a layer of double thickness, and turning the double layer back and setting it against the outer face of the insole to form an inwardly inclined 60 two-ply lip.
21. That improvement in methods of making insoles which consists in applying adhesive to the feather portion of an insole, separating said 65 feather portion into an upper layer and a lower layer, the upper layer being about half as thick as the lower layer, folding the outer half of the upper layer back and pressing it down flat against the inner half so that the adhesive will cause 70 the two portions to become permanently attached to each other, thereby forming a double upper layer which is substantially as thick as the lower layer but only about half as wide, and folding the upper layer inwardly against the surface of the 75

insole to form an inwardly inclined double lip along the inner edge of the feather portion of the insole.

22. That improvement in methods of making insoles which consists in applying cement to the outer face of an insole at the feather portion only, cutting an outside channel in said insole to form an outer channel flap which extends inwardly from the edge of the insole a distance equal to the feather portion thereof, thereby reducing said feather portion, turning the outer half of the channel flap inwardly and pressing it down upon the inner half so that the cement will stick the two portions together, thereby forming a double layer of material substantially equal in thickness to the reduced feather portion of the insole, and bending said double layer back and setting it against the outer face of the insole, thereby producing a double lip which will tend to remain in an inwardly inclined position.

23. That improvement in methods of making insoles which consists in applying cement to the feather portion of an insole, channeling said feather portion inwardly from the edge face of the insole in a plane substantially parallel to its inner face to reduce said portion and to form a continuous outer channel flap of about half the thickness of the remaining portion of the feather, snipping off the channel flap across the toe end of the insole to separate the continuous flap into two parts, one being located along each margin of the insole, folding the outer portion of one of said flaps back against the inner portion there-

of so that the cement will cause the two portions of the flap to stick permanently together to form a double flap of substantially the same thickness as the reduced feather portion of the insole, turning the double flap back against the outer face of the insole to form an inwardly inclined double lip, and repeating the process on the flap located at the opposite margin of the insole.

24. That improvement in methods of making insoles which consists in applying cement to the outer face of an insole along its marginal portion only, channeling into said marginal portion inwardly from the edge face of the insole a distance sufficient to form a relatively wide feather, said channel being spaced from the outer face of the insole a distance approximately equal to one third of the thickness of the insole, thereby forming a relatively thin channel flap, cutting off the channel flap at the toe end of the insole to separate it into two parts located at opposite margins of the insole, folding the channel flap at one margin back upon itself to form a double flap approximately equal in thickness to the feather portion of the insole, turning the double flap over against the outer face of the insole and setting it in such position to form an inwardly inclined double lip which will resist being brought into an upright position, applying a stiffening solution to the outer surface of the double lip, and repeating the process on the channel flap located at the opposite margin of the insole.

EVERETT E. MURPHY.
